UNITED STATES PATENT OFFICE.

EDWARD BROCKUP, OF CARTERET, NEW JERSEY.

COMBINATION-LOCK.

1,364,698.

Specification of Letters Patent.

Patented Jan. 4, 1921.

Application filed June 30, 1920. Serial No. 393,208.

To all whom it may concern:

Be it known that I, EDWARD BROCKUP, a citizen of Poland, residing at Carteret, in the State of New Jersey, have invented certain new and useful Improvements in Combination-Locks, of which the following is a specification.

The main object of this invention is the provision of a combination lock having means whereby the same may be opened without the aid of any key, but only by one having acquaintance with the proper sequence of steps in the manipulation of the various indices on the face of the lock.

15 The above and other objects will become apparent in the description below, in which characters of reference refer to like-named parts in the drawings.

Referring briefly to the drawings, Figure 20 1 is a front elevational view of my lock.

Fig. 2 is a plan view of the complete lock.

Fig. 3 is a cross-sectional view taken on the line 3—3 of Fig. 4.

Fig. 4 is a similar view with the front 25 cover plate removed.

Fig. 5 is a cross-sectional view taken on the line 5—5 of Fig. 4.

Referring now in detail to the drawings, the numeral 1 represents the casing of my lock, having a front cover plate 3 and a rear cover plate 4. A shackle 2 is slidably mounted in said casing, and is provided with arcuate grooves or recesses 17 and 18 in its leg 2^a, and with an arcuate groove or recess 19 in its leg 2^b. A recess 21 is also provided in the leg 2^b below the recess 19, being bounded by two parallel, horizontal walls between which a latch 14 is adapted to be engaged.

40 Between the covers 3 and 4 are mounted, one above the other, rotatable cylindrical pins 8 and 10, as shown, lying partly in the path of the leg 2^a, and each having an arcuate recess 20 therein for the purpose of

45 allowing free passage of the leg 2^a when each of said pins is turned into the position shown by the pin 10 in Fig. 5. A similar pin 9 is mounted between said covers and lying partly in the path of the leg 2^b.

50 Said pins extend through the front cover 3, and on the extensions are mounted hexagonal rotatable handle members 8^a, 9^a and 10^a, upon each of which is engaged an arrow. Surrounding each member 8^a, 9^a, and

10^a, is a graduated circle having any desired 55 indicating marks, as, for instance, numerals 1 to 10, inclusive. In the particular form of my lock illustrated, the respective positions of the handles for opening the lock are indicated in Fig. 1.

Within the frame 1 is a compartment 22 in which a rigid pin or shaft 11 is vertically mounted. A coiled spring 13 surrounds the enlarged portion 12 of said pin and is secured at the bottom to said frame and at 65 the top to said pin. A latch 14 is pivotally mounted on said shaft and is provided with a substantially U-shaped recess adapted to surround the leg 2^b, and particularly the recess 21 in said leg. An extension 15 of said 70 latch projects through the rear cover 4, and is adapted to be moved a short distance so as to disengage the latch 14 from the recess 21. The spring 13 normally urges the latch 14 into engagement with the recess 21.

75 A coiled spring 16 is located in the lower part of the frame beneath the leg 2^b, normally urging the shackle 2 upward.

Assuming, now, that the lock is in closed position, and that it is desired to open the 80 same. First the handles 8^a, 9^a, and 10^a are rotated into the positions shown in Fig. 1, and then the extension 15 of the latch 14 is moved slightly to the left (Fig. 5). Thereupon the grooves 17, 18, and 19 being all in 85 the position shown by the groove 17 in Fig. 5, will allow free passage upward of the legs 2^a and 2^b of the shackle 2, and the force of the spring 16 will raise the said shackle, since the latch 14 has also been disengaged 90 from the recess 21.

Thus it is apparent that I have provided a compact and durable combination lock which cannot be opened by one not acquainted with the combination, and which requires 95 no key.

I claim:

A device of the class described comprising a frame having a front and a rear cover, a shackle slidably mounted in said frame, 100 arcuate grooves in the legs of said shackle, pins pivotally mounted between said covers, said pins being mounted partly in the paths of said legs, said pins normally engaging said grooves in said legs, and being adapted 105 to be rotated so as to bring said grooves in said pins adjacent said legs to allow free passage of said legs, index handles attached

to said pins outside said front cover, graduations upon said front cover surrounding said handles, a shaft supported in vertical position in said frame, a latch pivoted on 5 said shaft, a coiled spring surrounding said shaft and normally urging said latch against one of said legs, a recess in said last-named

leg, a recess in said latch surrounding said last-named leg, said latch having an extension projecting through said rear cover and 10 adapted to be moved so as to disengage said latch from said recess in said leg.

In witness whereof I affix my signature.
EDWARD BROCKUP.
